[57] **ABSTRACT**

The specification discloses salicylanilides and halogenated salicylanilides wherein either or both the aniline or salicyl rings are substituted with a member of the class consisting of phenoxy and halophenoxy groups and the use of these compounds as effective germicides particularly in detergent compositions, such as soap bars.

21 Claims, No Drawings

SUBSTITUTED SALICYLANILIDES

This application is a continuation of my United States application Ser. No. 764,040, filed Sept. 25, 1968, which in turn is a continuation of my United States application Ser. No. 511,989, filed Dec. 6, 1965.

The present invention relates to a new class of germicides.

It is well known that halogenated salicylanilides have germicidal properties. The use of such compounds is described in Angew. Chem., 1955, 67, 145 (D. Jerchel and H. Oberheiden) and J. Pharm. Sci., 1961, 50, 831 (H. Lemaire, C.H. Schramm and A. Cahn).

It has now been discovered that the effectiveness of such compounds as germicides can be increased by modifying their molecular structure by replacing at least one of the H atoms attached to C in either or both of the aromatic rings of the salicylanilide residue by a phenoxy or halogenated phenoxy group. It has also been found that the similar introduction of a phenoxy or halogenated phenoxy group into salicylanilide itself results in a useful germicide. As halogen, chlorine and bromine are particularly suitable.

Accordingly, the invention provides a salicylanilide wherein at least one of the H atoms attached to C in either or both of the aromatic rings of the salicylanilide residue is replaced by a phenoxy or halogenated phenoxy group of from zero to the total number of the remaining H atoms attached to C in said aromatic rings in replaced by halogen.

The compounds where the phenoxy substituent is in the aniline ring of the salicylanilide are preferred.

Another aspect of the invention is a germicidal composition containing a salicylanilide of the invention.

The salicylanilides of the invention have been found to be effective in soap against both gram-positive (Staph. aureus) and gram-negative (E. coli) bacteria. Accordingly, another aspect of the invention is a saponaceous composition containing a salicylanilide of the invention.

It has also been discovered that mixtures of the salicylanilides of the invention with certain well known germicides for use in detergent compositions, namely, 3,4,4'-trichlorocarbanilide (TCC), 3,5,4'-tribromo-salicylanilide (TBS) and 2,2'-dihydroxy-3,5,6,3',5',6'-hexachloro-diphenylmethane (G 11) display synergistic bacteriostatic effect. The invention further includes synergistic bacteriostatic mixtures of the salicylanilides of the invention with 3,4,4'-trichlorocarbanilide, 3,5,4'-tribromosalicylanilide or 2,2'-dihydroxy-3,5,6,3',5',6'-hexachloro-diphenylmethane. Accordingly, another aspect of the invention is a germicidal composition containing a synergistic bacteriostatic mixture of a salicylanilide of the invention and 3,4,4'-trichlorocarbanilide, 3,5,4'-tribromosalicylanilide or 2,2'-dihydroxy-3,5,6,3',5',6'-hexachloro-diphenylmethane.

The salicylanilides of the invention can be prepared by a variety of methods. For example, one method is the condensation of a haloaminodiphenylether (A) with a halogen-substituted salicylic acid (B), A and B being prepared by standard methods for the preparation of such compounds; another method is the direct halogenation of a phenoxy salicylanilide.

EXAMPLE 1.

3,5,3'-trichloro-6'-(p-chlorophenoxy)-salicylanilide.

A slurry of 1.8 g. of 4,4'-dichloro-2-amino diphenyl ether and 1.4 g. 3,5-dichlorosalicylic acid in 20 ml. of xylene was refluxed with 0.3 ml. of phosphorus trichloride for 3 hours and the reaction mixture filtered hot. The solution on cooling deposited 1.6 g. (51 Percent) of 3,5,3'-trichloro-6'-(p-chlorophenoxy)-salicylanilide which was recrystallized from a benzene-petroleum ether mixture to give crystals of m.p. 195°-196°C.

The finger imprint rating of the compound was determined by the method described in J. Pharmacol. Sci., 1961, 50, 827.

The value obtained was 4.0. This is the maximum value obtainable in this test. By comparison, TCC gave a value of 1.3.

The minimum inhibitory concentration in parts per million (M.I.C.) of the compound was determined by a standard procedure and the value of 0.3 obtained. For purposes of comparison, the MIC of TCC, TBS and G 11 by the same method is given.

10	TCC	TBS	G 11
	M.I.C.	0.2	0.5

In each of the following Examples, the compounds were prepared by a method similar to that described in Example 1.

EXAMPLE 2.

3,5,3'-trichloro-6'-(o-chlorophenoxy)-salicylanilide.

Melting point 193°-195°C; M.I.C. 1.0.

EXAMPLE 3

5,3'-(o-chlorophenoxy)-salicylanilide.

Melting point 173°-175°C; M.I.C. 0.3.

EXAMPLE 4

3,5,3'-trichloro-6'-phenoxy-salicylanilide.

Melting point 151°-152°C; M.I.C. 0.8.

EXAMPLE 5

5,3'-dichloro-6'-phenoxy-salicylanilide.

Melting point 163°-164°C; M.I.C. 0.1.

EXAMPLE 6

3'-chloro-6'-(o-chlorophenoxy)-salicylanilide.

Melting point 142°-144°C; M.I.C. 3.0.

EXAMPLE 7

3'-chloro-6'-(p-chlorophenoxy)-salicylanilide.

Melting point 169°-171°C; M.I.C. 1.0.

EXAMPLE 8

3'-chloro-6'-phenoxy-salicylanilide.

Melting point 152°-154°C; M.I.C. 0.24.

EXAMPLE 9

The M.I.C. of mixtures of the compounds of Examples 1-8 with TCC, TBS and G 11 were obtained and compared with the MIC to be expected. The results are shown in Table I below:

- indicates no synergism

+ indicates synergism

++ indicates marked synergism

Example	TCC	TBS	G 11
1	++	++	+
2	++	++	+
3	+	+	+
4	+	+	+
5	+	+	+
6	-	-	-
7	+	+	+
8	++	++	+

EXAMPLE 10

3,5,3'-Trichloro-6'-(2,4,5-trichlorophenoxy)-salicylanilide.

A mixture of 11.7g (0.036 moles) of 2,4,5,4'-tetrachloro-2'-aminodiphenyl ether, 8.3g (0.04 moles) of 3,5-dichloro salicylic acid and 1.8 ml. of phosphorus trichloride in 125 ml. of chlorobenzene was refluxed for 3 hours, filtered hot and allowed to crystallize. 12.9g (70.1 percent) of a solid (melting point 194°-7°C) was obtained which, after 4 recrystallizations from chlorobenzene had a melting point of 201-4°C, and was shown to be pure by thin layer chromatography on silica, eluted with petroleum ether: acetone: acetic acid, (95:5:2).

The M.I.C. of the compound was 0.5
In each of the following Examples, the compounds were prepared by a method similar to that described in Example 10.

EXAMPLE 11

5,3'-dichloro-6'-(p-chlorophenoxy)-salicylanilide. MIC 0.1

EXAMPLE 12

3,5,3'-tribromo-6'-(p-bromophenoxy)-salicylanilide. MIC 0.6

EXAMPLE 13

6'-(p-chlorophenoxy)-salicylanilide. MIC 0.5

EXAMPLE 14

5-chloro-6'-phenoxy-salicylanilide. MIC 0.6

EXAMPLE 15

3,5-dichloro-6'-phenoxy-salicylanilide. MIC 0.5

EXAMPLE 16

3,5-dichloro-6'-(p-chlorophenoxy)-salicylanilide. MIC 0.2
m.p. 158°-9°C.

EXAMPLE 17

3,5-dichloro-6'-(o-chlorophenoxy)-salicylanilide. MIC 0.9
m.p. 155°-6°C.

EXAMPLE 18

The MIC of mixtures of the compounds of Examples 11-15 with TCC, TBS and G11 were compared with the MIC to be expected, as in Example 9. The results are shown in Table II below.

Example	TCC	TBS	G11
11	+	+	+
12	++	++	+
13	-	-	-
14	+	+	+
15	++	+	+

The halogenated amino diphenyl ethers employed in Examples 1 and 10 were synthesized by zinc/dilute acid reduction of the corresponding nitro compound using a five to six-fold ex-

cess of zinc. The nitro compound was obtained via an Ullmann synthesis using conditions similar to those described by R.V. Henley, J. Chem. Soc., 1222 (1930).

What is claimed is:

5. 1. A salicylanilide having from 0 to 8 halogen atoms selected from the class consisting of chlorine and bromine on the salicylanilide residue and wherein one of the aromatic carbon atoms in the aniline ring bears a substituent selected from the class consisting of phenoxy and halogenated phenoxy groups having from 1 to 3 halogen atoms selected from the class consisting of chlorine and bromine.
2. A salicylanilide having from 0 to 8 halogen atoms selected from the class consisting of chlorine and bromine on the salicylanilide residue and wherein the carbon atom in the 15 6' position in the aniline ring bears a substituent selected from the class consisting of phenoxy and halogenated phenoxy groups having from 1 to 3 halogen atoms selected from the class consisting of chlorine and bromine.
3. A salicylanilide according to claim 1 in which the 20 halogenated phenoxy substituent is a p-chloro-phenoxy group.
4. A salicylanilide according to claim 1 in which the halogen substituent or substituents in the aromatic ring or rings is chlorine.
5. 3,5,3'-trichloro-6'-(p-chlorophenoxy)-salicylanilide.
6. 3,5,3'-trichloro-6'-(o-chlorophenoxy)-salicylanilide.
7. 5,3'-dichloro-6'-(o-chlorophenoxy)-salicylanilide.
8. 3,5,3'-trichloro-6'-phenoxy-salicylanilide.
9. 5,3'-dichloro-6'-phenoxy-salicylanilide.
10. 3'-chloro-6'-(o-chlorophenoxy)-salicylanilide.
11. 3'-chloro-6'-(p-chlorophenoxy)-salicylanilide.
12. 3'-chloro-6'-phenoxy-salicylanilide.
13. 3,5,3'-trichloro-6'-(2,4,5-trichlorophenoxy)-salicylanilide.

14. 5,3'-dichloro-6'-(p-chlorophenoxy)-salicylanilide.
15. 3,5,3'-tribromo-6'-(p-bromophenoxy)-salicylanilide.
16. 6'-(p-chlorophenoxy)-salicylanilide.
17. 5'-chloro-6'-phenoxy-salicylanilide.
18. 3,5-dichloro-6'-phenoxy-salicylanilide.
19. 3,5-dichloro-6'-(p-chlorophenoxy)-salicylanilide.
20. 3,5-dichloro-6'-(o-chlorophenoxy)-salicylanilide.

21. A salicylanilide having from zero to eight halogen atoms on the salicylanilide residue and wherein one of the aromatic carbon atoms in the aniline ring bears a substituent selected from the class consisting of phenoxy and halogenated phenoxy groups having from one to three halogen atoms.
